TOKEN TICKET DISPENSERS

Friedrich Heil and Wilhelm Muller, Frankfurt am Main, Germany, assignors to Telefonbau und Normalzeit G.m.b.H., Frankfurt am Main, Germany, a firm of Germany

Filed Oct. 15, 1957, Ser. No. 690,372

20 Claims. (Cl. 235—101)

This invention relates to dispensers for post stamps and for similar tokens of predetermined monetary value as may be used for various purposes. Such dispensers may be used for dispensing tickets entitling the holder thereof to a predetermined service other than a postal service. Hereinafter post stamps and like tokens in ticket-like form representing a predetermined monetary value will be referred to by the generic term of "token tickets."

It is a general object of the invention to provide improved token ticket dispensers having a means enabling the purchasers of tickets to select among several species of post stamps, or other token tickets, and having another means enabling the purchasers to select the desired number of the selected species, or kind, of post stamps, or other token tickets.

It is another more specific object of the invention to provide a token ticket dispenser of the aforementioned character which is easier to operate and whose structure is less complex than comparable prior-art token ticket dispensers.

Another object of the invention is to provide a token ticket dispenser of the aforementioned character having a plurality of simple locking means, or lock-out means, for assuring the required sequences of operation of its constituent parts, and for preventing improper operation of the dispenser.

Another object of the invention is to provide an apparatus of the aforementioned character having means for readily correcting errors which may be made by a purchaser of token tickets in adjusting the quantity selector of the apparatus.

Another object of the invention is to provide an apparatus of the aforementioned character having improved counting means for the various monetary values of the various kinds, or species, of token tickets dispensed by it.

Still another object of the invention is to provide an apparatus of the aforementioned character having improved cutting means for severing the token tickets dispensed by the apparatus from the reel of token tickets still remaining in the apparatus.

Further objects, advantages and features of this invention will become apparent as the following description proceeds, and the features of novelty which characterize this invention will be pointed out with particularly in the claims annexed to, and forming part of, this specification.

For a better understanding of the invention reference may be had to the accompanying drawings illustrating the invention, wherein

Fig. 1 is a diagrammatic isometric view or assembly drawing of a mechanism embodying the invention wherein certain details which appear in other figures have been omitted;

Fig. 2 is a less diagrammatic isometric view of the quantity selector mechanism which is an integral part of the structure of Fig. 1, Fig. 2 showing some of the parts which have been omitted in Fig. 1;

Fig. 3 is a less diagrammatic isometric view of the

2

species selector mechanism which is an integral part of the structure of Fig. 1;

Fig. 4 is an isometric view of an operating key and of a locking mechanism which is operatively associated with it and which form integral parts of the structure of Fig. 1;

Fig. 5 is an isometric view of some parts of the dispensing mechanism of a ticket reel and of a casing for the dispensing mechanism and the ticket reel, these parts being constituent elements of the structure of Fig. 1;

Figs. 6 and 7 are isometric views showing two different positions of a counting and control mechanism which forms an integral part of the mechanism of Fig. 1; and Fig. 8 shows a sensing mechanism which may be used

15 instead of the control mechanism of Figs. 6 and 7.

Referring now to the drawings, and more particularly Figs. 1 and 2 thereof, numeral 101 has been applied to designate a shaft supporting the two gears 104, 105 and three cams 134, 112 and 234. Gear 104 and cam 134

20 have been clearly shown in Fig. 2 but not in Fig. 1. Shaft 101 supports also an indicating or number disc 121 and an operating knob 123 for disc 121. The right end of shaft 101 supports a selecting sector or dial 102 which is loosely mounted on it. Selecting sector or dial 102 is

25 provided with ten cut-out portions, or apertures, for inserting the tip of one's forefinger when it is desired to dial a predetermined number of units indicated on dial 102. Ratchet 103 is pivotally mounted on one of the two sides of dial 102, and acted upon by a spring 103a, tending to

30 establish cooperative engagement between ratchet 103 and gear 104. When dial 102 is being turned in clockwise direction (as seen in Figs. 1 and 2), ratchet 103 engaging gear 104 causes shaft 101 to make a turn equal to that of dial 102. A frame 122 having a window through

35 which the numbers inscribed on number disc 121 may be read off is arranged in front of number disc 121, and the same number as selected by dial 102 appears always behind the window in frame 122. Dial 102 is acted upon by a spring (not shown) which biases dial 102 to the

40 initial or zero position thereof.

Shaft 120 is arranged parallel to shaft 101 and supports a disc 110 having a pin 111 adapted to engage and to cooperate with gear 105. Shaft 120 supports also a spur gear 119 meshing with a spur gear 152 on main driving

45 shaft 136. When shaft 120 and disc 110 are being turned by gears 152, 119 in the direction which has been indicated in Fig. 2 by an arrow (clockwise), pin 111 engages the lower surface of a latch 106 pivotally mounted at 106b which is biased by a spring 107. Latch 106 has

50 a projection or nose 106a normally engaging gear 104. When pin 111 engages latch 106, nose 106a is lifted momentarily against the bias of spring 107 out of engagement with gear 104. When pin 111 is pivoting latch 106 it is also engaging gear 105 and then moves the same a

55 distance equal to the circular pitch of that gear. Thus shaft 101 is being stepped backward, i.e., turned in consecutive steps whose direction is opposite to the direction of its movement when acted upon by dial 102. When shaft 101 has been returned to its initial position, or zero

60 position, wherein the figure zero appears in the window of frame 122, pin 111 and shaft 120 are not any longer in the position to move gear 104 in backward direction gear 104 being provided with a gap 108 between some of its teeth limiting backward movement, or precluding continued backward movement thereof by parts 111 and 120.

65 Shaft 101, gears 104, 105 and cams 134, 112 and 234 and number disc 121 operate as a storage or memory device. The numbers dialed at each operation of dial 102 are stored by the angular movement or movements of shaft 101. Dial 102 can be operated several times

70 in sequence, in which case the dialed numbers are being added. A complete revolution of shaft 101 and of num-

ber wheel 121 corresponds to the figure 50 which figure then appears in the window of frame 122.

Number disc 121 and operating knob 123 form an integral part of a coupling sleeve 129 which can be displaced on shaft 101 in a direction longitudinally thereof, but which is positively coupled with shaft 102 for joint rotary motion with it. Spring 124 wound around shaft 101 biases number disc 121 to its normal position shown in Figs. 1 and 2. Preparatory to turning shaft 101 manually by means of knob 123, the latter must be shifted from left to right, as seen in Figs. 1 and 2. Then number disc 121 abuts against pin 125, shifting the latter in a direction longitudinally thereof from the left to the right. This causes engagement of the right pointed end of pin 125 with a bent, cam-shaped portion 106b' of latch 106, as a result of which projection 106a is being lifted out of engagement with gear 104. Thereafter it is possible to rotate shaft 101 by means of knob 123 as, for instance, for correcting an error which may have occurred when operating dial 102.

Species selector lever 132 is provided for selecting the kind or denomination of stamps desired as, for instance, 1 cent stamps, 3 cent stamps, 5 cent stamps, 8 cent stamps, et cetera. Lever 132 is pivotally mounted on pin 132a. The upper end of lever 132 forms a handle 132b, whereas its lower end cooperatively engages a sleeve 137 slidably mounted on driving shaft 136 for the purpose of selectively shifting sleeve 137 to either side. Lever 132 is provided with a multiperforated transverse arm 132c arranged close to the upper end thereof. The perforations 132d in arm 132c are adapted to be engaged by a pin 135a on lever 135 (Fig. 2). Lever 135 is pivoted at 135b and controlled by cam 134 mounted on storage or memory shaft 101. As long as shaft 101 is in the initial or zero position thereof, pin 135a is out of engagement with perforations 132d and, therefore, lever 132 may be adjusted at will by means of handle 132b, thus enabling to select the desired kind of stamps. On the other hand, if any given number has been stored by storage or memory shaft 101, then cam 134 has pivoted lever 135, and pin 135a has entered one of the perforations 132d in transverse arm 132, making it impossible for lever 132 to be pivoted about pin 132d, i.e. locking lever 132 in position.

Driving shaft 136 supports a set of spur gears 301, 302 . . . 305, 306. Each of these gears is adapted to drive one—and only one—of the spur gears 307, 308 . . . 311, 312 of the dispensing devices 313, 314 . . . 317, 318. Driven gear 307, 308 . . . 311, 312 are axially displaced in regard to driving gears 301, 302 . . . 305, 306, the amount of displacement being different for each cooperating pair of gears 301, 307; 302, 308; et cetera. In the position of the parts shown in Fig. 1 driving gear 306 meshes with driven gear 312 of the dispensing device 318. Driving gear 305 is axially displaced one step from the driven gear 311 with which it may be brought into meshing engagement by an axial movement of shaft 136. The spacing between cooperating pairs of gears, i.e. gears which may be brought into meshing engagement increases progressively from right to left (as seen in Fig. 1), the axial displacement of driving gear 301 from driven gear 307 being five steps.

Assuming the species selector lever 132 to have been shifted three steps in order to select another species, or kind, of stamps, as a result driving gear 303 is caused to mesh with driven gear 309 of dispenser 315, while all other driving gears 301, 302 . . . 305, 306 are out of mesh with their respective driven gears 301, 302 . . . 311, 312.

Counting device 203 mounted on shaft 214 is always positively connected to driving shaft 136 by a pair of meshing spur gears 211, 212, of which the former is mounted on driving shaft 136 and the latter on shaft 214. Shaft 136 supports a pair of coupling discs 260 arranged to both sides of a cooperating coupling disc 261 mounted

on shaft 214. Discs 260, 261 form cooperating abutments causing shaft 214 to be shifted jointly with shaft 136 to the left or right, as the case may be, whenever the former is being shifted in a direction longitudinally thereof. Counting device 203 is made up of three stacks of discs 205, 206, 207 provided on the cylindrical surfaces thereof with pins 203a in the shape of teeth. The discs 204 in stack 205 count numbers having one digit, the discs in stack 206 count numbers having two digits, and the discs in stack 207 count numbers having three digits. Counting device 203 has been shown in the drawing but diagrammatically, and such counting devices do not need to be described in detail since they are well known in the art. The object of counting device 203 is to control the adding totalizer or counter 200, i.e. to transfer the movements of shaft 136 to device 200 in such a way as to control device 200 in accordance with the value of the stamps which have been dispensed. When the counting device 203 is being shifted 20 in an axial direction, one of the discs 204 of each of the stacks 205, 206, 207 is in registry with one of the three transmission gears 202 of the adding totalizer 200 and thus in position to operate gears 202. The discs 204 operating transmission gears 202 correspond to the 25 monetary value of the stamps in the particular dispensing device 313-318 then being operated by driving shaft 136 which, in the position of the parts shown in Fig. 1, is the dispensing device 318. At each revolution of driving shaft 136, resulting in unwinding of one single stamp 30 having a given denomination from a reel 338 (see Fig. 5) of stamps of that denomination in one of the dispensing devices 313-318, counting device 203 operates the adding totalizer 200 so as to add on the value of that particular stamp.

35 Referring now to Figs. 1 to 5, and more particularly to Fig. 5, the dispensing devices 313-318 shown each comprises a drum 319a mounted on a bush 319 adapted to receive a shaft (not shown). The width of each drum 319a is equal to the width of the particular kind, or species, of stamps which it is intended to dispense. The cylindrical surface of the dispensing drum of each dispensing device 313-318 is provided with angularly displaced pairs of pins 320 adapted to engage the perforations formed between immediately adjacent stamps. The 40 distance between each pair of angularly displaced pins 320 is equal to the length of the particular species, or kind, of stamps to be dispensed by the particular dispensing device.

45 As best shown in Fig. 5, the left side of each drum 319a is provided with a plurality of angularly displaced radial slots 322. The angles between pairs of pins 320 are equal to the angles between slots 322. Pin 324 mounted on lever 323 is adapted to enter slots 322. Each dispensing device 313-318 is provided with one lever 323 50 supporting a pin 324 jointly forming a crank mechanism adapted to be driven by, and to move in synchronism with, the respective driven gears 307-312 of the dispensing devices. Rotation of one of gears 307-312, and of lever 323 and pin 324 associated with that particular gear 55 causes pin 324 to engage one of the radial slots 322 and to turn the drum about an angle equal to the angle enclosed between immediately adjacent pairs of pins 320, or immediately adjacent slots 322 in one of the sides of the drum. As a result, one stamp is being unwound from storage reel 338 and moved forwardly by one of the drums 60 of one of the dispensing devices 313-318.

65 Each storage reel 338 is arranged inside of a casing, or housing 335, having a removable cover, or side wall 337, enabling to readily get access to and replenish any given storage reel 338. Contiguous dispensing devices 313-318 are separated by partitions 380, 381 forming compartments each adapted to receive one storage reel 338 and housing 335. As shown in Fig. 5, each of the casings, or housings 335 is provided with a lateral rib 336 engaging 70 a groove 380a in partition 380.

If desired, a stamp counter 339 may be built into each casing or housing 335. Counter 339 is operated by means of a rocking lever 371 which, in turn, is operated by pins 372 provided on the left side of each dispensing drum of each dispensing device 313-318.

Electric motor 400 is provided for driving shaft 136 and counting device 203. Pulley 416 is being driven by motor 400 by the intermediary of intermediate gearing 401. Belt 415 operates pulley 402 forming an integral part of a first clutch, and a pulley 403, forming an integral part of a second clutch. Reference numeral 116 has been applied to indicate the left portion of said first clutch, and reference numeral 221 has been applied to indicate the left portion of said second clutch (Figs. 1 and 2). Sleeve or bush 117 is slidably mounted on shaft 154, and the left side of sleeve or bush 117 is provided with teeth adapted to cooperatively engage teeth on the right side of clutch member 116. Cams 118 and 150 are integral parts of sleeve or bush 117. The lower end of lever 130 pivoted at 130a engages cam 150. Lever 130 is biased by spring 130b tending to disengage the lower end of lever 130 from cam 150. The upper end of lever 130 is adapted to be acted upon by an electromagnet 131 tending to move lever 130 into the position wherein lever 130 engages cam 150. Sleeve or bush 117 is acted upon by a spring (not shown) tending to move sleeve or bush 117 toward the left (as seen in Fig. 2), causing engagement of the teeth thereof with the teeth on clutch member 116. As long as lever 130 engages cam 150, sleeve or bush 117 is precluded from being shifted to the left into engagement with clutch member 116. Cam 118 is engaged by the lower end of lever 114 pivoted at 114a and under the action of spring 115, tending to cause engagement under pressure of lever 114 and cam 118. The upper arm of lever 114 is engaged by, and under the control of, a cam 112 fixedly mounted on storage shaft 101. When storage shaft 101 is being turned, lever 114 is being pivoted by cam 112, as a result of which the lower end of lever 114 disengages from cam 118, thus releasing sleeve or bush 117 to move from its right position to its left position.

Sleeve or bush 117 is provided with an arm 151 projecting through a rectangular aperture 152a in spur gear 152. This arm establishes a permanent positive coupling of parts 117 and 152 in both directions of rotation thereof. A short length of shafting 155 is positively connected to spur gear 152 and provided with a transverse pin 153. Pin 153 projects into a pair of slots 137a provided in coupling sleeve 137 on driving shaft 136. As a result of this arrangement of parts, driving shaft 136 is always positively connected to coupling sleeve 137 in both directions of rotation, irrespective into which position shaft 136 may have been shifted by means of the species selector lever 132, and coupling sleeve 137, engaged, and operated, by the lower end of selector lever 132.

The electric circuit of motor 400 may be closed by suitable switch means, i.e. by a contact 405 adapted to be operated by a key 404 pivoted at 404a. (See Figs. 1 to 4, particularly Fig. 4.) In case that dial 202 has been operated before operating key 404, the latter needs to be depressed but for an instant, and may be released immediately thereafter. Projection 414 of key 404 cooperating with locking pin 410 then locks key 404 in position until such time as storage shaft 101 has returned to its initial or zero position, and the number of stamps previously selected by operation of selector dial 102 has been dispensed. The mechanisms provided for achieving this result comprises the following parts: Pin 409 slidably mounted in sleeve 406 and under the bias of helical spring 408 inside of sleeve 406 projecting with one end thereof into an appropriate recess 109 on gear 105 mounted on storage or memory shaft 101. The aforementioned mechanism further comprises a spring 411 arranged in the hollow end 413 of pin 409, biasing locking pin 410, and a transverse pin 412 projecting through a longitudinal slot

in locking pin 410, precluding the latter from dropping out of the hollow end 413 of pin 409. Recess 109 is in registry with the tip of pin 409 when storage shaft 101 is in the initial or zero position thereof. This particular position of parts 409, 105 and 101 has been illustrated in Fig. 4. Operation of shaft 101 by dial 102 causes pin 409 to be pushed out of recess 109 to the left (as seen in Fig. 4). At the same time springs 408 and 413 are being compressed. Locking pin 410 cannot move to the left as long as the projection 414 of key 404 is arranged in its path. However, when key 404 is being depressed and projection 414 moved out of the path of locking pin 410, the latter snaps to the left, and then precludes projection 414 and key 404 from returning to the initial positions thereof. Contact 405 remains closed as long as key 404 is locked in its depressed position. Projection 414 and key 404 are unlocked only upon return of the right end of pin 409 into the cooperating recess 109 in gear 105. Then key 404 returns to its initial position, thereby opening contact 405. Motor 400 is then de-energized, the selected number of stamps having been dispensed.

Each of the dispensing devices 313 . . . 318 is provided with a knife 327 to cut-off those stamps which have been unwound from storage reel 338. (See Figs. 1 and 25.) Each knife 327 is provided with a guiding frame structure 326 to move it along a straight path, and with an operating lever 370 of which one end is pivotally connected to knife 327, one end operated by a cam 329, and a point intermediate both ends journaled to the guiding 30 frame structure 326. The operating cams 329 of all knives 327 are mounted on a common shaft 330. Gear 227 on shaft 330 meshes with gear 226 on auxiliary shaft 226a upon which the number wheels 201 of the adding totalizer or counter 200 are loosely mounted. Shaft 226a 35 may be driven by meshing gear 220, the two parts 224, 221 of a clutch and pulley 403.

Part 223 of coupling 221, 223 in the shape of a shaft-supported sleeve is under the bias of a spring (not shown) and comprises a cam portion 223a. The biasing spring of 40 part 223 tends to shift the latter from right to left into cooperative engagement with part 221. Lever 224 pivotally supported at 240 is adapted to engage cam portion 223a to preclude coupling sleeve 223 from being shifted to the left under the bias of the aforementioned spring. 45 Lever 224 is acted upon by a spring 247 tending to move lever 224 to the position shown in Fig. 3 wherein clutch members 223 and 221 are separated. The shaft 240 supporting lever 224 is provided with a pawl 243 adapted to engage, and to cooperate with, a control arm 242 of key 50 222. Key 222 is pivotally supported at 241 and raises control arm 242 when being depressed. When key 222 is depressed, control arm 242 raised and pawl 243 thereby turned in counterclockwise direction, as seen in Fig. 3, this causes lever 224 to be so pivoted as to release sleeve-shaped clutch member 223. Depressing key 222 beyond 55 the point required to release clutch member 223 causes pawl 243 to drop off nose 242a on control arm 242. This permits pivotal movement of lever 224 and re-engagement thereof with cam portion 223a on part 223. As a 60 result, cam portion 223a and part 223 are moved against spring action from left to right, i.e. to the position shown in Fig. 3, upon completion of one revolution of these two parts. The upper end of control arm 242, is adapted to operate a switch means, e.g. contact 229, arranged in the 65 electric circuit of motor 400. Angle member 245 forming an integral part of control arm 242 engages, and is controlled by, a cam 244, mounted to turn jointly with coupling sleeve 223. Cam 244 causes contact 229 to remain closed during an entire revolution of cam 244, irrespective of whether or not key 222 is being released. 70 Key 222 can only be operated, i.e. depressed, when storage or memory shaft 101 is in the zero position thereof. To this end cam 234 on storage or memory shaft 101 controls pin 230 the lower end of which is arranged in the path of the movement of a projection 233

of lever 224. In the initial or zero position of storage shaft 101 the upper end of pin 230 engages a recess 235 in cam 234 and, therefore, the lower end of pin 230 is situated sufficiently far from projection 233 of lever 224 not to interfere with pivotal movement of lever 224 about shaft 240. If storage shaft 101 is not in its initial or zero position or, in other words, if the selected number of stamps has not yet been unwound from its respective storage reel, then pin 230 slides on the radially outer surface of cam 234, thereby precluding lever 224 from being pivoted.

Assuming key 222 to be operated while storage or memory shaft 101 is in its initial or zero position: then motor 400 is being switched on as a result of closing of contact 229. Simultaneously both coupling members 221 and 223 are caused to engage each other for one full revolution of pulley 403. Gears 220, 226 and 227 then operate shaft 330, cams 229 and cam-controlled knives 327. As a result, all the post stamps previously unwound from their respective storage reel 338 by the operation of dispensing devices 313-318 are cut-off, and allowed to drop into a hopper (not shown). Rotation of auxiliary shaft 226a causes the adding totalizer 200 to be reset to its initial or zero position. The specific means for achieving this end have not been illustrated in the drawing since such means are well known in the art and have no immediate bearing upon the present invention. Upon releasing of key 222 pawl 243 slides along the slanting lower surface of projection 242a of control arm 242, temporarily stretching or expanding spring 246. Eventually pawl 243 enters the recess formed above projection 242a and then assumes again the position shown in Fig. 3.

Key 236a may be inserted into the key-hole 236b of a lock 236 for controlling a linkage 237 adapted to lock key 222 in its inoperative position. When key 222 is locked by parts 236 and 237, no stamps can be dispensed by the apparatus.

A push button 345 is arranged adjacent the front of each dispensing drum of the several dispensing devices 313-318 (Fig. 5). As shown in Figs. 6 and 7 push-button 345 is cooperatively related to a contact 351. Contact 351 controls the energizing circuit of electromagnet 131 shown in Figs. 1 and 2. Referring now more particularly to Figs. 6 and 7, the control element 340 of contact 351 is under the control of two parts, i.e. lever 343 and the control end of a pin 350 forming a coaxial extension of push-button 345. Each pin 350 is secured by a bracket 350a to one of partitions 380 (Figs. 5, 6 and 7). Lever 343 is mounted on the same shaft 243a as a sensing element 342 having a sharp edge 342a much like a knife's cutting edge. Sensing element 342 is provided to explore the positions of control discs 339a forming a part of the adding totalizer or counter 339 (see also Fig. 5). Each control disc 339a forms an integral part of one of the number wheels of the adding totalizer or counter 339, and each control disc 339a is provided with a narrow groove or slot (not shown) extending parallel to shaft 343a. If all the number wheels of the adding totalizer or counter 339 are in their initial or zero positions, all the aforementioned narrow grooves or slots are in alignment, making it possible for the sharp edge 342a to enter simultaneously into all of the aforementioned grooves or slots in control discs 339a. This, in turn, causes lever 343 to pivot in clockwise direction, as seen in Figs. 6 and 7. As a result, control element 340 is released, i.e. not supported any longer by lever 343, thus permitting contact 351 to close. Closing of contact 351 causes energization of electro-magnet 131. Therefore lever 130 is being operated by electro-magnet 131 and henceforth precludes any rotary motion of driving shaft 136.

If and when one of the housings 335 is being removed from the rest of the structure, this means removal of the particular lever 343 from the contact 351 with which it cooperates. As a result, control element 340 loses its

support, and contact 351 closes, again energizing magnet 131 and precluding any rotary motion of shaft 136.

The adding totalizer or counter 339 comprises three control discs 339a, and three number wheels, each associated with one of these control discs (Fig. 6). Each control disc 339a and each number wheel corresponds to a different digit. Hence, all control discs 339a and all number wheels will be in the same position when the adding totalizer or counter 339 indicates either zero, or one thousand. In case that a given container or housing 335 is being replenished with a new storage reel 338 supporting 1000 post stamps, sensing edge 342a drops into the edge-receiving grooves or slots in control discs 339a, causing lever 343 to release control element 340. This, in turn, causes closing of contact 351. Exerting pressure upon push-button 345 causes shifting of pin 350 against the bias of spring 350b to the position shown in Fig. 6 wherein its pointed end engages control element 340, thus opening contact 351. In this position pin 350 is latched-in by lever 343 engaging a recess 350c in pin 350. Now the dispensing device is ready to be operated.

As soon as at least one stamp has been unwound from its respective storage reel 338, at least one of the three control discs 339a of the respective adding totalizer or counter 339 is being shifted out of its zero position. Hence sensing blade 342 shifts lever 343 in counterclockwise direction, and the latter releases pin 350 to the action of spring 350b. Now lever 343 supports control element 340, previously held in position by the joint action of pin 350 and lever 343, and thus contact 351 remains open.

In the modification illustrated in Fig. 8 the adding totalizer or counter 339 and the mechanism associated with the same (shown in Figs. 6 and 7) have been omitted, and replaced by another structure. The latter comprises a sensing lever 345 pivotally mounted at 345b and engaging an aperture in a frame 349 behind which a strip of post stamps 348 is being moved in a direction longitudinally thereof. Sensing lever 345 is biased by spring 345a against the post stamps 348 under the frame 349. When the last post stamp 348 has been removed, sensing lever 345 loses its support and is then pivoted by spring 345a in counterclockwise direction. Lever 346 is supported by the same pin as lever 345, and moves simultaneously in a counterclockwise direction with lever 345. Lever 346 is adapted when moved counterclockwise to close contact 347 arranged in the energizing circuit of electromagnet 131.

The clutch member 117 for driving shaft 136 is under the control of an arm 128 mounted on shaft 128a (Fig. 2). Shaft 128a supports arm 127 under the action of spring 127a. Normally arm 128 is situated out of the path of clutch member 117, permitting the latter to engage its cooperating clutch member 116. However, if knob 123 is being shifted from left to right and turned manually in order to adjust the position of storage or memory shaft 101, then pin 126 on number disc 121 engages lever or arm 127, causing arm 128 to be moved into the path of clutch member 117, and thus precluding cooperative engagement of the two parts 117 and 116 of the coupling for shaft 136.

The operation of the above structure has been described, in part, along with the description of the structure and, therefore, but little needs to be added in regard to the operation of the above described token ticket dispenser or vending machine.

Preparatory to operation of the machine, lock 236 (Fig. 3) must be unlocked to unlock key 222. Thereafter lever 122 is operated, i.e. placed into the particular position which is correlated to the desired kind or species of stamps. Thereupon dial 102 is operated in accordance with the number of stamps of the particular kind or species desired. Turning of storage or memory shaft 101 by means of dial 102 causes select-

ing lever 132 to be locked in position by operation of cam 134 and coupling member 117 to be released by operation of cam 112 and lever 114. Subsequent operation of key 404 then starts motor 400. Key 404 though only depressed for an instant, or momentarily, remains locked in its operative position (by virtue of the operation of the mechanism shown in Fig. 4) until storage or memory shaft 101 has returned to its initial or zero position. The number of revolutions of driving shaft 136 is equal to the number of stamps selected by dial 102 for any given species. At each revolution of driving shaft 136 storage shaft 101 is turned back one step. When storage shaft 101 is back to its initial or zero position, lever 114 separates parts 116 and 117 of the clutch or coupling for operating driving shaft 136.

It will be apparent that the above operations may be repeated in regard to any kind, or species, of stamps desired. The monetary value of each kind, or species, of stamps in the process of being dispensed is being transmitted from driving shaft 136 to the counting device 203 and counter or adding totalizer 200, the former being coupled by gears 211, 212 with shaft 136. Counter or adding totalizer 200 indicates the total value of the stamps ready to be dispensed.

Operation of key 222 causes the stamps ready to be dispensed to be dispensed. Lever 224 releases part 223 of clutch 223, 221 then engaging part 221 thereof. As a result shaft 330 is being operated simultaneously operating all the knives 327 of all dispensing devices 313-318. At the same time counter or adding totalizer 200 is reset to its initial or zero position.

It will be apparent from the foregoing that the quantity selector 102 is adapted to be shifted from a predetermined initial or zero position to a plurality of ultimate positions of which each stands for a quantity of stamps, or other token tickets. The storage or memory shaft 101 under the control of quantity selector 102 is adapted to perform angular movements proportional to a shift of quantity selector 102 from said initial position to one of said plurality of ultimate positions. The apparatus further comprises a plurality of dispensing devices 313-318 of which each includes a ticket storage reel 338, and one of a plurality of transport drums. The apparatus further comprises a first plurality of equidistantly spaced driven spur gears 307-312 of which each is associated with one of the aforementioned plurality of dispensing devices, or plurality of transport drums, to operate one of said plurality of dispensing devices or transport drums. Mounted on the dispensing devices operating shaft or transport-drums-operating shaft 136 is a second plurality of spur gears 301-306, the driving spur gears, the spacing of which increases in progressive steps from one side of shaft 136 to the other. The manually operable species selector 132, 132b is adapted to shift driving shaft 136 in a direction longitudinally thereof to a plurality of predetermined positions. Driving spur gears 301-306 are spaced on shaft 136 in such a way as to permit meshing engagement of each of driven spur gears 307-312 with but one of driving spur gears 301-306. Perforations 132d on lever 135 and cam 134 form a locking mechanism for lever 132. Disc 110 and pin 111 are resetting means for shaft 101 to return shaft 101 to its initial position. Gap 108 is a means for precluding overshooting of the original position of shaft 101 during the resetting operation. Both lever 114 and 130 are means for precluding untimely coupling of automatic coupling or clutch 116, 117. Switch 404, 405 shown in Fig. 4 is under the control of a locking mechanism shown in detail in Fig. 4 which, in turn, is under the control of storage or memory shaft 101. Counter 200 is adapted to be driven by computing device 203 which, in turn, is adapted to be driven by storage shaft 136. Discs 260, 261 are means for shifting computing device 203 jointly with shaft 136 in a direction longitudinally there-

of to adjust computing device 203 in accordance with the monetary unit value of the token tickets determined by the position of species selector 132, 132b. Cam 234 and rod 230 are integral parts of a locking device for clutch or coupling 221, 223. Parts 323, 324 form a crank mechanism adapted to engage grooves 322 (Fig. 5) in transport drums 313-320 (Fig. 1). Each crank 323, 324 and the grooves 322 on each of the transport drums forms a stepping mechanism for moving transport drums 313-320 forwardly in a number of successive steps, rather than by a continuous motion. The ratio at which gears 307-312 are being driven by one of driving gears 301-306 is such as to result in a full forward step of each of the transport drums of dispensing devices 313-318 for each revolution of shaft 136. The distance transport pins 320 are being moved at each step of one of the transport drums is equal to the length of the stamps transported by the respective transport drum, or equal to the distance between contiguous pairs of stamp-engaging pins 320 on the respective transport drum. The angle between contiguous grooves 322 in any given transport drum is equal to the angle between contiguous pairs of stamp engaging pins 320 on the same transport drum.

It will also be apparent from the foregoing that though the mechanisms associated with each dispensing device 313-318, or transport drum, respectively, are the same, in principle, the individual mechanisms may vary on account of variations in the sizes of stamps, and on account of variations of the monetary value of different species of stamps.

Having disclosed a preferred embodiment of our invention it is desired that the same be not limited to any particular structure disclosed. It will be obvious to any person skilled in the art that many modifications and changes may be made without departing from the broad spirit and scope of the invention. Therefore it is desired that the invention be interpreted as broadly as possible and that it be limited only as required by the prior state of the art.

We claim as our invention:

1. In a token ticket dispenser the combination of a manually operable quantity selector adapted to be shifted from a predetermined initial position to a plurality of ultimate positions, a storage shaft under the control of said quantity selector adapted to perform angular movements proportional to a shift of said quantity selector from said initial position to one of said plurality of ultimate positions, a plurality of dispensing devices each associated with one of said plurality of dispensing devices, a first plurality of dispensing devices to operate one of said plurality of dispensing devices, a dispensing-devices-operating shaft, a manually operable species selector adapted to shift said dispensing-devices-operating shaft in a direction longitudinally thereof to a plurality of predetermined positions, a second plurality of gears spaced on said dispensing-devices-operating shaft in such a way as to permit meshing engagement of each of said first plurality of gears with but one of said second plurality of gears, and means dependent on the setting of said storage shaft for rotating said dispensing-devices-operating shaft.

2. A token ticket dispenser as specified in claim 1 comprising a locking mechanism under the control of said storage shaft controlling said species selector to lock said species selector in position upon angular movement of said storage shaft out of said initial position thereof.

3. A token ticket dispenser as specified in claim 1 comprising means driven by said dispensing-devices-operating shaft for resetting said storage shaft from one of said plurality of ultimate positions to said initial position, said means being adapted to move said storage shaft one predetermined step at each revolution of said dispensing-devices-operating shaft.

4. A token ticket dispenser as specified in claim 1 comprising an electric motor for driving said dispensing-devices-operating shaft, automatic coupling means adapted to selectively couple said dispensing-devices-operating shaft with said electric motor and to uncouple said dispensing-devices-operating shaft from said electric motor, and a sensing lever under the control of said storage shaft adapted to preclude coupling of said automatic coupling means in said initial position of said storage shaft to stop said dispensing-devices-operating shaft when said storage shaft is in said initial position thereof.

5. A token ticket dispenser as specified in claim 1 comprising an electric motor for driving said dispensing-devices-operating shaft, an automatic coupling adapted to selectively couple said dispensing-devices-operating shaft with said electric motor and to uncouple said dispensing-devices-operating shaft from said electric motor, a first lever under the control of said storage shaft, said first lever being adapted to preclude coupling of said automatic coupling when said storage shaft is in said initial position thereof to stop said dispensing-devices-operating shaft when said storage shaft is in said initial position thereof, an electric switch responsive to an operating condition in said token ticket dispenser, an electro-magnet under the control of said electric switch, and a second lever under the control of said electro-magnet to preclude coupling of said automatic coupling on occurrence of said operating condition.

6. A token ticket dispenser as specified in claim 1 comprising an electric motor for driving said dispensing-devices-operating shaft, an electric circuit for energizing said motor, a normally open manually operable electric switch for controlling said electric circuit, a locking mechanism for said electric switch, and means under the control of said storage shaft to control said locking mechanism to maintain said switch closed as long as said storage shaft is turned out of said initial position thereof, said locking mechanism control means being adapted to permit opening of said switch upon return of said storage shaft to said initial position thereof.

7. A token ticket dispenser as specified in claim 1 comprising a counter, a computing device adapted to be driven by said dispensing-devices-operating shaft to operate said counter, and means for shifting said computing device jointly with said dispensing-devices-operating shaft in a direction longitudinally thereof to adjust said computing device in accordance with the monetary unit value of the token tickets determined by the position of said species selector.

8. A token ticket dispenser as specified in claim 1 comprising a plurality of cutting knives each operatively associated with one of said plurality of dispensing devices to cut-off the token tickets being dispensed, a plurality of operating levers each for operating one of said plurality of cutting knives, a plurality of cams each adapted to operate one of said plurality of levers, a common shaft supporting said plurality of cams, an electric motor for operating said common shaft, a manually operable coupling adapted to selectively couple said common shaft with said electric motor and to uncouple said common shaft from said electric motor, a locking device under the control of said storage shaft precluding manual operation of said coupling unless said storage shaft is in said initial position thereof, and automatic means limiting to one the number of revolutions which said common shaft can perform at a time.

9. A token ticket dispenser as specified in claim 1 comprising an electric motor, a first coupling means adapted to couple said dispensing-devices-operating shaft with said electric motor and to uncouple said dispensing-devices-operating shaft from said motor, a sensing lever under the control of said storage shaft, said sensing lever being adapted to uncouple said first automatic coupling means in said initial position of said storage shaft to stop said dispensing-devices-operating shaft when said storage

shaft is in said initial position thereof, a plurality of cutting knives each operatively associated with one of said plurality of dispensing devices to cut-off the token tickets being dispensed, a common shaft for jointly operating said plurality of cutting knives, a second coupling means adapted to selectively couple said cutting knives operating shaft with said electric motor and to uncouple said cutting knives operating shaft from said motor, manually operable means for coupling said coupling means to cause said electric motor to drive said cutting knives operating shaft, and a locking device under the control of said storage shaft precluding operation of said manually operable means and driving of said cutting knife by said electric motor unless said storage shaft is in said initial position thereof.

10. In a token ticket dispenser the combination of a manually operable quantity selector dial adapted to be turned from an initial position to a plurality of ultimate positions, a storage shaft under the control of said dial adapted to perform angular movements proportional to a shift of said dial from said initial position to one of said plurality of ultimate positions, a cam on said storage shaft, a plurality of dispensing devices each including a rotatable transport drum adapted to move a strip of token tickets in a direction longitudinally thereof, a first plurality of gears each associated with a transport drum of one of said plurality of dispensing devices to operate said transport drum thereof, a dispensing devices-operating shaft, a manually operable species selector adapted to shift said dispensing devices operating shaft in a direction longitudinally thereof to a plurality of selecting positions, a locking mechanism for said species selector under the control of said cam on said storage shaft for locking said species selector in position upon angular movement of said storage shaft out of said initial position thereof, a second plurality of gears spaced on said dispensing devices operating-shaft in such a way as to permit meshing engagement of each of said first plurality of gears with but one of said second plurality of gears, and means depending on the setting of said storage shaft for rotating said dispensing-devices-operating shaft.

11. A token ticket dispenser as specified in claim 10 comprising a plurality of token ticket storage reels each for supplying said transport drum of one of said plurality of dispensing devices with a strip of token tickets of a predetermined length, a plurality of stepping mechanisms each operatively associated with said transport drum of one of said plurality of dispensing devices to turn said transport drum in steps equal in length to the length of the token tickets of the strip of token tickets supplied to said transport drum, each of said plurality of stepping mechanisms being driven by one of said second plurality of gears, and the ratio at which each of said second plurality of gears being driven by one of said first plurality of gears being such as to result in one forward step of said transport drum of each of said plurality of dispensing devices for each full revolution of said dispensing devices operating shaft.

12. A token ticket dispenser as specified in claim 10 comprising a plurality of transport drums each having angularly displaced pairs of transport pins on the cylindrical surface thereof and each having angularly displaced grooves on one of the lateral surfaces thereof, the angles of displacement of said grooves being equal to the angles of displacement of said pairs of pins, a plurality of crank mechanisms each comprising a pin adapted to engage sequentially said angularly displaced grooves on one of the lateral surfaces of one of said plurality of transport drums to cause a stepping motion of said one of said plurality of transport drums, and each of said plurality of crank mechanisms being adapted to be rotated by one of said second plurality of gears.

13. A token ticket dispenser as specified in claim 10 comprising an electric motor for driving said dispensing devices-operating shaft, automatic coupling means

adapted to selectively couple said dispensing devices-operating shaft with said electric motor and to uncouple said dispensing devices-operating shaft from said electric motor, said automatic coupling means being biased to the coupling position thereof, means under the control of said storage shaft precluding said coupling means from coupling said electric motor and said dispensing devices-operating shaft when said storage shaft is in said initial position thereof, and electromagnetic means responsive to the absence of token tickets on said transport drum of any of said plurality of dispensing devices for precluding said coupling means from coupling said electric motor and said transport-drums-operating shaft when all the token tickets on said transport drum of any of said plurality of dispensing devices are being dispensed.

14. A token ticket dispenser as specified in claim 10 comprising a plurality of counters each operatively related to said transport drum of one of said plurality of dispensing devices to count the value of the token tickets dispensed by each of said transport drum, a plurality of electric switches each under the control of one of said plurality of counters, electro-magnetic means under the control of said plurality of switches, and a locking mechanism under the control of said electromagnetic means precluding continued operation of said dispensing devices-operating shaft when any of said plurality of counters reaches a predetermined operating position thereof.

15. A token ticket dispenser as specified in claim 10 comprising a plurality of pivotally mounted sensing levers each operatively related to said transport drum of one of said plurality of dispensing devices and each adapted to slide loosely on a strip of token tickets, a plurality of electric switches each under the control of one of said plurality of sensing levers, electromagnetic means under the control of said plurality of switches, and a locking mechanism precluding continued operation of said dispensing-devices-operating shaft in response to pivotal movement of one of said plurality of sensing levers.

16. A token ticket dispenser as specified in claim 10 comprising a plurality of counters each operatively related to said transport drum of one of said plurality of dispensing devices to individually count the monetary value of the token tickets dispensed by said transport drum of each of said plurality of dispensing devices, a plurality of electric switches each biased to the closed position thereof and each under the control of one of said plurality of counters and allowed to move to said closed position when said one of said plurality of counters is in the zero position, a plurality of manual operators each for one of said plurality of switches to manually move each of said plurality of switches to the open position thereof, and a plurality of locking means each operatively related to one of said plurality of switches for locking said one of said plurality of switches in said open position upon manual opening thereof by one of said plurality of manual operators until one of said plurality of counters controlling said one of said plurality of switches is moved out of the zero position thereof, electro-magnetic means under the control of said plurality of switches, and a locking mechanism under the control of said electromagnetic means precluding continued operation of said dispensing devices-operating shaft when any of said plurality of switches is in the closed position thereof.

17. In a token ticket dispenser the combination of a substantially cylinder-segment-shaped quantity selector dial adapted to be turned from an initial position to a plurality of ultimate positions, a gear mechanism adapted to be operated by said dial, a storage shaft adapted to be turned by said gear mechanism to perform angular movements proportional to each shift of said dial from said initial position to said plurality of ultimate positions, a number disc mounted on said storage shaft, a plurality

of dispensing devices each including a rotatable transport drum each adapted to move a strip of token tickets in a direction longitudinally thereof, a first plurality of gears each operatively related to said transport drum of one of said plurality of dispensing devices to effect a stepped forward movement thereof, a motor driven dispensing devices-operating shaft, a manually operable species selector adapted to shift said dispensing devices-operating shaft in a direction longitudinally thereof to a plurality of selecting positions, lock-out means for said species selector under the control of said storage shaft precluding operation of said species selector when said storage shaft is out of said initial position thereof, a stepping mechanism operated by said dispensing devices-operating shaft 10 operating said gear mechanism for resetting said storage shaft from one of said ultimate positions to said initial position, means precluding said stepping mechanism from resetting said storage shaft beyond said initial position, a second plurality of gears spaced on said dispensing devices-operating shaft in such a way as to permit meshing engagement of each of said first plurality of gears with but one said second plurality of gears and means dependent on the setting of said storage shaft for rotating said dispensing-devices-operating shaft.

25 18. A token ticket dispenser as specified in claim 17 comprising manually operable means on said number disc permitting shifting of said number disc in a direction longitudinally of said storage shaft, and means responsive to a shift of said number disc in a direction 30 longitudinally of said storage shaft to render said gear mechanism ineffective to permit re-adjustment of said storage shaft by said manually operable means on said number disc.

19. In a token ticket dispenser the combination of a 35 manually operable quantity selector adapted to be turned from an initial position to a plurality of ultimate positions, a gear coupling mechanism adapted to be operated by said quantity selector, a storage shaft adapted to be turned by said gear coupling mechanism to perform

40 angular movements proportional to each shift of said dial from said initial position to said plurality of ultimate positions, a number disc mounted on said storage shaft, a manual operator forming an integral part of said number disc, manually operable means for uncoupling 45 said gear coupling to permit adjustment by said manual operator of the angular position of said storage shaft, a plurality of dispensing devices including a plurality of pivotally mounted transport drums adapted to be engaged by strips of token tickets and to move said strips in the 50 direction of rotation of said transport drums at the point of engagement of said strips, a plurality of gear mechanisms each operatively related to one of said plurality of transport drums to effect a stepped forward movement thereof, an electric motor, a dispensing devices-operating shaft adapted to be driven by said motor, a manually 55 operable species selector adapted to shift said dispensing devices-operating shaft in a direction longitudinally thereof to a plurality of selecting positions, lock-out means for said species selector under the control of said

60 storage shaft precluding operation of said species selector when said storage shaft is out of said initial position thereof, a stepping mechanism operated by said dispensing devices-operating shaft operating said gear coupling mechanism for resetting said storage shaft from one of 65 said ultimate positions to said initial position, means precluding said stepping mechanism from resetting said storage shaft beyond said initial position, and a plurality 70 of gears spaced on said dispensing devices-operating shaft in such a way as to permit meshing engagement of each of said plurality of gear mechanisms with but one of said plurality of gears.

20. In a token ticket dispenser the combination of a manually operable quantity selector adapted to be shifted from a predetermined initial position to a plurality of ultimate positions, a storage shaft under the control of

said quantity selector adapted to perform angular movements proportional to a shift of said quantity selector from said initial position to one of said plurality of ultimate positions, a plurality of dispensing devices each including a rotatable transport drum adapted to be engaged by one of said plurality of strips of token tickets to move said strip of token tickets in steps of predetermined length in the direction of rotation of said transport drum at the point of engagement thereof by one of said plurality of strips, a first plurality of equidistantly spaced 10 coaxially arranged gears each operatively related to said transport drum of one of said plurality of dispensing devices, a dispensing-devices-operating shaft for said plurality of gears arranged parallel to the common axis thereof, a plurality of spaced gears on said dispensing-devices-operating shaft having a spacing of progressively increasing length each adapted to mesh with but one of

5
15

said first plurality of gears, means for shifting said dispensing-devices-operating shaft in a direction longitudinally thereof to change meshing pairs of said first plurality of gears and of said second plurality of gears, and means depending on the setting of said storage shaft for rotating said dispensing-devices-operating shaft.
